MATCH PACKET HOLDER

George H. Dufour, Oak Park, Ill., assignor to
 Marshall Field & Company, Chicago, Ill., a corporation of Illinois

Application April 10, 1933, Serial No. 665,295

8 Claims. (Cl. 206—33)

My invention relates to a match packet casing and has particular reference to a casing having a metallic member with a holder for a match packet telescopically mounted therein adapted to be slidably positioned in said casing, and when moved farther into the casing the matches are caused to project out of the holder so they can be easily grasped with the fingers.

Another and further object of my invention is the provision of a match packet holder which thoroughly protects the matches from ignition while in the pocket of the user and thereby avoids any danger of accidental ignition of the matches, yet provides a convenient casing by means of which the matches can be withdrawn from the packet when desired.

Another and further object of my invention is the provision of a match packet holder particularly adapted for use with a packet whereby the matches are ignited as they are drawn from the holder, with the casing being formed in such manner that all danger of premature ignition of the matches is avoided and danger of burning the fingers or hands is also avoided.

Another and further object of my invention is the provision of a match holder which is easily separable so that the match packet can be easily placed in the holder and the holder inserted in the casing.

Another and further object of my invention is the provision of a match case holder having a plurality of openings in one edge thereof in alignment with the matches in the packet and the packet holder so that by pressing upon the base of the holder the holder and the matches are forced upward into the casing and the ends of the matches project through the holder. Upon being ignited as they are pulled from the holder the match is completely free of the holder before combustion of the match head takes place, thereby removing all danger of premature combustion of the match pack or burning of the matches.

These and other objects of my invention will be more fully and better understood by reference to the accompanying sheet of drawings and in which—

Figure 1 is an elevational view partially in section of my improved match packet holder;

Figure 2 is a sectional view on lines 2—2 of Figure 1; and

Figure 3 is an end elevational view of the match packet in position in the holding member.

Referring now specifically to the drawing and in which like reference characters refer to like

parts throughout, a casing 10 is shown having a plurality of openings 11, 11 in one edge thereof and having its opposite end open to receive the match packet holder 12. The casing 10 has recesses in each side thereof as shown particularly in Figures 1 and 2, to form finger openings at the side of the casing 10. The match packet holder 12 has short side walls 13 and 14 which are oppositely disposed, inwardly turned and adapted to engage the base portion of the usual commercial form of match packet 15 having matches 16, 16 positioned therein, the heads of the matches being at the lower part of the match pack 15, with frictional striking surfaces 17, 17 adjacent the open end of the match pack 15 so that as the matches are withdrawn from the pack 15 the heads in passing between the frictional surfaces 17, 17 are automatically ignited.

The walls 13 and 14 of the member 12 are comparatively short and have oppositely disposed curved spring tabs 18, 18 formed thereon, the outer sides of which frictionally engage the inner wall surfaces of the member 10 so that the member 12 is frictionally held in position in the casing 10, and may be moved to varying positions as may be desired.

Finger extension pieces 19, 19 are provided on the member 12 which are integrally formed with the side members 13 and 14 and are shaped to conform generally to the finger openings in each side of the member 10, these portions being positioned so that they form complete closure members for the openings in each side of the member 10. The height of the member 10 is sufficient so that when the device is closed the ends of the matches project approximately up to the end of the casing 10 in which the openings 11, 11 are positioned and therefore when the match packet is closed the matches do not project from the casing and are completely protected in the pocket of the user.

In operation, a standard packet of matches 15 is inserted in the holder 12 by being pushed into the holder from one side thereof, and thereafter the holder, including the packet of matches, is placed in the casing 10, with the lower edge of the member 12 in register with the lower edge of the casing 10 adjacent the one side thereof, with the ends of the matches projecting slightly into the openings 11, 11 at the opposite end of the case. The packet of matches and holding member 12 in this position are held by the frictional contact of the members 18, 18 against the inner side of the casing.

110

When it is desired to withdraw a match from the casing the holder 12 is pushed upward in the casing as much as may be desired, its limit of travel being determined by the length of the 5 matches which project out of the pack 15, in which position the matches will project from the casing 10 as shown in dotted lines in Figure 1. The operator thereupon grasps one end of the match and in pulling it from the case the match is automatically ignited as it passes between the friction surfaces 17. The operator can thereupon push the match packet holder 12 back into its original position by pressure upon the ends of the matches or by grasping the lower edge of the base member 12 in the finger openings in the sides of the casing 10 and pulling the member 12 and match pack back as desired.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

25. I claim:

1. A holder comprising a casing having a plurality of spaced openings therein in alignment with the matches of a packet, and a member telescopically arranged in said casing and having 30 means thereon adapted to hold said packet of matches.

2. A holder comprising a casing open at one of its ends and having a plurality of spaced openings at its opposite end in alignment with the 35 matches of a packet, and a member having upturned spaced portions thereon adapted to hold said packet of matches adapted to be telescopically positioned in said casing.

3. A holder comprising a casing open at one 40 of its ends and having a plurality of spaced openings at its opposite end in alignment with the matches of a packet, and a member having upturned spaced portions thereon adapted to hold said packet of matches adapted to be telescopically positioned in said casing and having means 45 thereon whereby the said member is held in said casing.

4. A holder comprising a casing open at one of

50 its ends and having a plurality of spaced openings at its opposite end in alignment with the matches of a packet, and a member having upturned spaced portions thereon adapted to hold said packet of matches adapted to be telescopically positioned in said casing and having means thereon whereby the said member is held in said casing.

5. A holder comprising a casing open at one of its ends and having a plurality of spaced openings at its opposite end in alignment with the 55 matches of a packet, and a member having upturned spaced portions thereon adapted to hold said packet of matches adapted to be telescopically positioned in said casing and having means thereon whereby the said member is held in said casing.

6. A holder comprising a casing open at one of its ends and having a plurality of spaced openings at its opposite end in alignment with the 60 matches of a packet, and a member having upturned spaced portions thereon adapted to hold said packet of matches adapted to be telescopically positioned in said casing and having means thereon whereby the said member is held in said casing.

65. A holder comprising a casing open at one of its ends and having a plurality of spaced openings at its opposite end in alignment with the matches of a packet, and a member having upturned spaced portions thereon adapted to hold said packet of matches adapted to be telescopically positioned in said casing and having means thereon whereby the said member is held in said casing.

70. A holder comprising a casing open at one of its ends and having a plurality of spaced openings at its opposite end in alignment with the matches of a packet, and a member having upturned spaced portions thereon adapted to hold said packet of matches adapted to be telescopically positioned in said casing and having means thereon whereby the said member is held in said casing.

its ends and having a plurality of spaced openings at its opposite end in alignment with the matches of a packet, and a member having upturned spaced portions thereon adapted to hold said packet of matches adapted to be telescopically positioned in said casing, and having means thereon whereby the said member is frictionally held in the said casing.

80. 5. A holder comprising a casing open at one of its ends and having a plurality of spaced openings at its opposite end in alignment with the matches of a packet, and a member having inwardly turned wall portions adapted to engage the base portion of said packet of matches and having yielding members thereon adapted to frictionally engage the inner walls of the casing member.

85. 6. A match packet holder comprising a casing open at one of its ends and having a plurality of spaced openings in its opposite end in alignment with the matches of a packet, and a member having oppositely disposed inwardly turned edges adapted to receive the base of said packet of matches, and having resilient members thereon adapted to frictionally engage the inner wall 100 of the casing.

90. 7. A match packet holder comprising a casing open at one of its ends and having a plurality of spaced openings in its opposite end in alignment with the matches of a packet, and a member having oppositely disposed inwardly turned edges adapted to receive the base of said packet of matches, and resilient members positioned on the edges of said members adapted to frictionally engage the walls of the casing on the inner sides 110 thereof.

95. 8. A match packet holder comprising, in combination, a casing open at one of its ends, and a packet holding member telescopically arranged in the open end of the said casing and having 115 means thereon adapted to engage a packet of matches, means at the opposite end of the casing for permitting the ends of the matches in the packet to project out of said end of the casing as the match packet holder is pushed into the 120 said casing.

100. GEORGE H. DUFOUR.

125.

105. 9. A match packet holder comprising a casing open at one of its ends and having a plurality of spaced openings in its opposite end in alignment with the matches of a packet, and a member having oppositely disposed inwardly turned edges adapted to receive the base of said packet of matches, and resilient members positioned on the edges of said members adapted to frictionally engage the walls of the casing on the inner sides 130 thereof.

110. 10. A match packet holder comprising a casing open at one of its ends and having a plurality of spaced openings in its opposite end in alignment with the matches of a packet, and a member having oppositely disposed inwardly turned edges adapted to receive the base of said packet of matches, and resilient members positioned on the edges of said members adapted to frictionally engage the walls of the casing on the inner sides 135 thereof.

115. 11. A match packet holder comprising a casing open at one of its ends and having a plurality of spaced openings in its opposite end in alignment with the matches of a packet, and a member having oppositely disposed inwardly turned edges adapted to receive the base of said packet of matches, and resilient members positioned on the edges of said members adapted to frictionally engage the walls of the casing on the inner sides 140 thereof.

120. 12. A match packet holder comprising a casing open at one of its ends and having a plurality of spaced openings in its opposite end in alignment with the matches of a packet, and a member having oppositely disposed inwardly turned edges adapted to receive the base of said packet of matches, and resilient members positioned on the edges of said members adapted to frictionally engage the walls of the casing on the inner sides 145 thereof.

125.
